Specification for Design.

Patented May 18, 1920.

Application filed December 30, 1919. Serial No. 348,501. Term of patent 14 years.

To all whom it may concern:

Be it known that we, ALPHONS G. MILLER and CHARLES McMULLEN, citizens of the United States of America, residing at Flemington, in the county of Hunterdon and State of New Jersey, have invented a new, original, and ornamental Design for a Lens, of which the following is a specification, reference being had to the accompanying drawing, forming a part thereof.

Figure 1 shows a front elevation of the lens illustrating our new design.

Fig. 2 is a section on the line 2—2 of Fig. 1.

Fig. 3 is a section on the line 3—3 of Fig. 1.

We claim:

The design for a lens, substantially as shown.

ALPHONS G. MILLER.
CHARLES McMULLEN.
